UNITED STATES PATENT OFFICE.

LAURITZ W. ANDERSEN, OF WATERBURY, CONNECTICUT.

CANDLE-SHADE HOLDER.

Application filed August 3, 1922. Serial No. 579,363.

To all whom it may concern:

Be it known that I, LAURITZ W. ANDERSEN, a citizen of the United States, residing at Waterbury, in the county of New Haven and State of Connecticut, have invented a certain new and useful Improvement in Candle-Shade Holders, of which the following is a full, clear, and exact description, reference being had to the accompanying drawings.

This invention is a novel construction of shade holder, and has for its object to provide a shade holder which shall be cheap and simple to manufacture and which will securely hold the shade when in use and will prevent wobbling, now so prevalent in the present type of candle shade holder.

Another object is to provide a simple form of shade holder which will have abundant strength to support a heavy shade. Another object of the invention is to provide a form of candle shade holder in which there will be no waste material in the fabrication of the same. With these various objects in view the invention consists in the novel features of construction and in the manner of combining or arranging the same all of which will be fully described herein-after and pointed out in the appended claims.

In the drawings forming a part of this specification Fig. 1 is a view showing one embodiment and use of my invention; Fig. 2 is a detail view of the clamp constituting a part of the shade holder; and Fig. 3 is a detail perspective view of one of the wings of said clamp; Fig. 4 is a detail view showing my improved form of clamp connected to the frame of a shield shade; Fig. 5 is a top plan view of the clamp and Fig. 6 is a plan view of the blank from which the wing of the clamp is formed.

Referring to the drawings A indicates the conventional form of candle and B the shade which in the present instance is shown connected to a circular frame C which in turn is attached to a flanged ring D through the stem of the integral tongues D' punched from the flanged ring and turned over the inner ring of the circular frame. The flanged ring which carries the shade has two supporting rods or wires E connected thereto, these rods or wires being in turn connected to the clamp as hereinafter explained. The clamp comprises two similar wings F comprising the curved jaw F' and the rear-

wardly extending handle portion F², the jaw portions F' being adapted to encircle and bind upon the circular candle holder or other objects. Each wing has a separate or independent pivotal connection and there is interposed between the said wings one common spring which acts upon both of the wings of the clamp. In practice I prefer to pivot the wings of the clamp to the wires which serve as supports for the shade or shield and this wire is bent centrally as shown at E' and is then carried in parallel directions as shown at E² to provide the proper point of attachment for the wings and it will be noted that at the juncture of the curved jaw F' and the handle portion F² there are punched out from the opposite edges of the jaw the tongues F³ which are coiled around the parallel portions E² of the wire and provide the proper connection between the jaws and the wire. The wire is then bent at right angles as indicated at E³ and then carried up and attached to the flanged ring as shown in Fig. 1 or connected to the shield frame G as indicated in Fig. 4. The ends of the handle portions F² are curved toward each other as indicated at F⁴ and in such inturned ends are fixed the opposite ends H' of the centrally disposed coil spring H which it will be noted occupies a position between the wings and also in alignment with the space between the parallel portions of the wire to which the wings are attached. By this method of assembly each wing is independent of the other to a certain extent. There is also a limited amount of movement between pivots of the wings and the axis of the coil spring during the opening and closing operations. By having the wings pivoted in the manner herein shown and applying the pressure in the manner set forth and at the same time providing two separate wires for supporting the shade or shield I am able to provide a clamp which will firmly hold upon the object to which it is affixed and a strong and steady support will be provided for any and all types of shades.

By making the wings from plain flat stock and rolling back the pivotal connections I avoid all waste of material and thereby materially reduce the cost of the article.

It will thus be seen that I provide an exceedingly simple and highly efficient construction of holder particularly adapted for holding a candle shade, but it will be under-

stood that it can also be used for other purposes.

Having described my invention, what I claim is:

- 5 1. In a device of the kind described, a pair of clamping jaws, parallel vertical wire members to which said jaws are pivotally connected, a spring arranged between said jaws and contacting at the rear ends with 10 the rear ends of said jaws, said wire members extending horizontally rearwardly and then vertically, and a shade frame attached to said vertically extending ends of said wire members.
- 15 2. In a device of the kind described, a pair of clamping jaws, parallel vertical wire members to which said jaws are pivotally connected, said jaws having tongues embracing said wire-members, the rear ends of said 20 jaws being turned inwardly toward each other, a coiled spring arranged between said jaws and having the ends extending rearwardly and in contact with the inturned ends of said jaws, said wire members extending horizontally rearwardly and then vertically; and a shade frame attached to the ends of said vertically extending wire members. 25
- 30 3. In a device of the kind described, a pair of clamping jaws, a wire having a central horizontal portion, parallel downwardly extending portions, horizontally extending portions and vertically extending end portions, said jaws being pivotally connected to said parallel downwardly extending portions of said wire, a shade frame connected to the ends of said vertically extending end portions of the wire, and a spring interposed between the jaws and contacting at its ends with the rear ends of 35 said jaws. 40

In testimony whereof, I hereunto affix my signature.

LAURITZ W. ANDERSEN.
